ALTERNATING CURRENT MERCURY VAPOR APPARATUS

Application filed January 12, 1928, Serial No. 246,123, and in Great Britain March 18, 1927.

This invention relates to alternating current mercury vapor apparatus of the vacuum type comprising an arc tube preferably of quartz, having at one end of the apparatus a 5 cathode and at the other end a pair of anodes.

It is well known that for the successful operation of such apparatus, the main difficulty to be overcome is that of readily starting the arc. In starting, the usual method is to 10 tilt the apparatus until a stream of mercury runs up the arc tube from each anode and connects with the cathode so as to complete the arc tube circuit, and then to bring the apparatus back to its normal position, the 15 apparatus being constructed so that the stream of mercury from each anode is interrupted as simultaneously as possible at the point where the two streams join the cathode. This operation is not, however, successful 20 unless means are provided for avoiding short circuiting of the two anodes.

It is well known that in such apparatus, as at present constructed, that is to say, in which the cathode is at one end of the arc tube, the 25 two anodes being at the other end of the said tube, this difficulty can be overcome by providing a web or ridge of quartz on the bottom of the arc tube for the purpose of separating the mercury in the two anodes.

30 We have now found that the difficulty referred to can also be overcome by forming a small channel or gutter, in the bottom of the tube, starting at the mouth of the capillary portion of the cathode, or if no capillary portion is used, starting at the end of the cathode itself, and extending to the part where the mercury returning to the anodes will divide.

The arc tube of the apparatus is preferably 35 made "V" shaped with the limbs of the "V" close together, the anodes being situated at the ends of the said tube and the cathode at the joint of the "V". The channel in this case extends across the joint of the "V" and may be formed in the quartz after the apparatus 45 has been shaped, and is produced by blowing and/or pressing the quartz at the desired place, after first softening the quartz in a blowpipe.

The principal object of the present invention is to provide an improved mercury vapor

arc tube in which the streams of mercury connected to each anode and the cathode are broken practically simultaneously so as to strike an arc when the tube is moved back to the operating position after having been 55 tilted to cause the mercury streams to flow together to complete the arc tube circuit.

A further object of the invention is to cheapen and improve the construction of 60 tubes of this character.

In order that the invention may be fully understood one manner of carrying it out in practice will be described with reference to the accompanying drawing in which Figures 1 and 2 are an elevation and plan respectively of an apparatus in accordance with the 65 invention.

The apparatus, which is preferably made of quartz, comprises a "V" shaped tube having limbs 1 and 2 each limb being provided 70 at its end with an anode 3 and 4. A short tube 5 connects the joint of the "V" with the cathode 6. The anodes and the cathode are in communication through tubes 7, 8 and 9 with the electrodes 10, 11 and 12. The tube 75 5 which is herein referred to as the capillary portion of the cathode, is provided at its upper portion with a channel or gutter 13 which extends across the joint of the "V" of the arc tube.

In operation the apparatus is tilted in the usual way and lowered to allow the mercury to return to the anodes. During the lowering, a portion of the mercury remains in the channel or gutter 13 in the form of a small 80 stream which connects with the mercury in the cathode vessel 6. The mercury flowing back to the two anodes by way of the divided arc tube 1 and 2 takes the form of two streams which are approximately equal in volume and 85 which are moving at the same rate. These two streams break away from the mercury in the channel or gutter 13 at practically the same instant and as this happens an arc is struck between whichever anode happens to be positive at the moment of breaking, and the mercury in the channel or gutter 13 which is connected with the cathode vessel 6. No 90 short circuit between the anodes 3 and 4 can take place because the mercury from 95 100

these anodes is flowing in the divided portion of the arc tube. Owing to the very small volume of mercury in the channel or gutter 13, this quickly vaporizes the arc travelling back 5 along the channel until it reaches its final position in the capillary portion of the cathode vessel.

By making the apparatus of V form according to the preferred construction so that 10 the axes of the anode vessels are at only a small angle to the centre line of the apparatus when viewed in plan, and not at right angles as is usual, this has the advantages of cheapening the construction and reducing 15 the overall width of the apparatus while the mercury can be so positioned as readily to flow into the arc tubes when the apparatus is tilted for starting. These two latter advantages can even further be increased if desired, if the anode vessels are placed with 20 their axes parallel to each other so that the anode vessels are as close together as is practicable. In fact, the limbs 1 and 2 can themselves be made parallel for example U 25 shaped; this is not, however, shewn in the drawing.

Having now particularly described and ascertained the nature of our said invention and in what manner the same is to be performed, we declare that what we claim is:—

1. An alternating current mercury vapor apparatus as defined in claim 6 in which the tube portions within which the anodes are located are positioned relatively close together.

2. An alternating current mercury vapor apparatus as defined in claim 6 in which the channel is of small capacity so that it will contain a relatively small amount of mercury 40 when the tube is returned to the operating position after it has been tipped to start the operation.

3. Alternating current mercury vapor apparatus comprising an arc tube and a pair of 45 anode tubes communicating therewith and forming acute angles with each other and joining said arc tube at substantially a common point so that mercury flowing therethrough will divide into substantially equal 50 streams for the several anode tubes, and a depression in the bottom of the arc tube along a line between the two anode tubes so that the streams of mercury flowing into the several anode tubes will separate from each other 55 and from the mercury remaining in the depression substantially simultaneously.

4. Alternating current mercury vapor apparatus comprising an arc tube having a cathode chamber at one end thereof, and a 60 plurality of anode tubes diverging from the other end of the arc tube at acute angles, said arc tube having a groove in its bottom substantially along the center thereof and extending from the cathode chamber to the 65 point where the anode tubes separate, said

groove being adapted to hold a thread of mercury in electrical contact with the cathode which will be almost instantly vaporized by the heat of the arc when struck.

5. Alternating current mercury vapor apparatus comprising an arc tube having a cathode chamber and a plurality of the anode chambers located therein, the bottom of said tube being V-shaped in plan and substantially at the same level in the two arms of the V so as to divide equally to the two anodes a stream of mercury flowing from the cathode and having a narrow depressed channel between the cathode and the inner vertex of said V with its bottom inclined downwardly from the vertex of the V toward the cathode, whereby the cathode will be connected by a narrow thread of mercury to streams of mercury in both arms of the V at the instant that they break apart.

6. Alternating current mercury vapor apparatus comprising an arc tube having a cathode and a pair of anodes located therein, said arc tube being divided so as to divide between the anodes a stream of mercury flowing toward the anode end of the tube, and having a narrow channel extending toward the cathode from the point in the tube where the mercury divides when it flows back to the anodes.

7. Alternating current mercury vapor apparatus comprising an arc tube having a cathode located therein and formed with joined tube portions within each of which an anode is located and a channel formed in the bottom of the tube and extending towards said cathode from the point where the tube portions meet.

8. Alternating current mercury vapor apparatus comprising an arc tube having diverging branches at one end thereof adapted to carry anodes and having its other end adapted to hold the cathode mercury and a narrow depressed channel in the bottom of said tube between the cathode and the point of division between the diverging branches adapted to hold a thread of mercury connected to the cathode when the streams of anode mercury have flowed into their respective branch tubes by the tilting of the tube 105 from the starting toward the operating position.

In testimony whereof we have signed our names to this specification.

FREDERICK REYNOLDS.
ARTHUR LEONARD LEES.
